(57) **CLAIM**

The ornamental design for an electronic display for a wearable device with animated graphical user interface, as shown and described.

DESCRIPTION

FIG. 1 is a front view of a first image of an electronic display for a wearable device with animated graphical user interface showing our new design;

FIG. 2 is an enlarged front view thereof, the graphical user interface is shown separately for clarity of illustration;

FIG. 3 is a front view of a second image thereof;

FIG. 4 is an enlarged front view thereof, the graphical user interface is shown separately for clarity of illustration;

FIG. 5 is a front view of a third image thereof;

FIG. 6 is an enlarged front view thereof, the graphical user interface is shown separately for clarity of illustration;

FIG. 7 is a front view of a fourth image thereof;

FIG. 8 is an enlarged front view thereof, the graphical user interface is shown separately for clarity of illustration;

FIG. 9 is a front view of a fifth image thereof;

FIG. 10 is an enlarged front view thereof, the graphical user interface is shown separately for clarity of illustration;

FIG. 11 is a rear view thereof;

FIG. 12 is a left view thereof;

FIG. 13 is a right view thereof;

FIG. 14 is a top view thereof; and,

FIG. 15 is a bottom view thereof.

The broken line showing of the wearable device in FIGS. 1, 3, 5, 7, 9, and 11-15 forms no part of the claimed design.

The appearance of the image transitions sequentially between the images shown in FIGS. 1, 3, 5, 7, and 9, and FIGS. 2, 4, 6, 8, and 10. The process or period in which an image transitions to another forms no part of the claimed design.
